UNITED STATES PATENT OFFICE.

CHARLES J. HOLUB, OF NEWPORT, KENTUCKY, ASSIGNOR TO THE PECK-WILLIAMSON HEATING & VENTILATING COMPANY, OF CINCINNATI, OHIO, A CORPORATION OF OHIO.

SHEET-METAL CUTTER.

1,122,598.

Specification of Letters Patent.

Patented Dec. 29, 1914.

Application filed July 10, 1913. Serial No. 778,270.

To all whom it may concern:

Be it known that I, CHARLES J. HOLUB, a citizen of the United States, and residing at Newport, in the county of Campbell and 5 State of Kentucky, have invented a new and Improved Sheet-Metal Cutter, of which the following specification is a full disclosure.

My invention relates to a device for the circular cutting of sheet metal blanks.

10 The object of the invention is to provide a simple and efficient device for cutting selective curves, the resultant blanks to be rolled up into approximately conical forms, constituting sheet metal structures of standard 15 and requisition in furnace and pipe manufacture.

Another object of the invention is the provision of convenient, effective and accurate means for selectively varying the dimensions 20 of the blanks.

Another object relates to the provision of means selectively determining the radii of the cuts.

By these provisions the longitudinal area 25 is predetermined, as well as the arcs of the boundary curve edges, enabling the production of any desired blank involving the structural principle.

The features of the invention are more 30 fully set forth in connection with the description of the accompanying drawings, forming a part of this specification, in which:—

Figure 1 is a side elevation of the machine. Fig. 2 is a sectional view on line 35 2—2, Fig. 1. Fig. 3 is a top plan view showing the blank in position for the first cut. Fig. 4 is a front elevation of the clamping jaws, partly in section to show the guide 40 pins.

The primary support is an I-beam 1, horizontally held in any desired manner, the front end having the cut-away portion 2, for supporting the cutter mechanism 3, see 45 Figs. 1 and 2. The cutter is of standard type having the jaws 4, shafts 5, connected by gears 6, 7, operated by crank 8, the cutter disks 9, 10, being fixed to the ends of shafts 5, the upper shaft having some play 50 in its bearings, so that the cutting edges can be adjusted by screw 11, the table 12 being alined with the cutting edges to support the cut end of the sheet metal lying between the jaws 4, the plane of the cutter disks being transverse to the I-beam. On the upper

rail of the I-beam is a saddle 13, adjustably supported by blocks 14 and bolts 15. A rotatable, adjustable radius bar support 16 is placed on the upper face of saddle 13, held in place by plate 17 and bolts 18, so as to 60 freely swivel. It is formed with a transverse orifice through which passes the radius bar 20, being adjustably secured by clamp bolts 21. Preferably a bracket 22 is upwardly extended from the saddle, a rail 23 being 65 mounted on the free end to support the weight of the radius bar in its arc of swing for the cutting operation. The saddle is positioned by stops 24, 25, adjustable on the I-beam, one margin of which bears the scale 70 26, with relation to which said stops are slidable. As shown in Figs. 1-3, the saddle engages stop 24, positioning the sheet metal blank with reference to the cutters for making the outer or longer arc incision, 75 indicated by dotted lines a—a, Fig. 3. To cut the inner or shorter curve, the saddle will be moved outwardly to contact the stop 25, positioning the parts for cutting the inner or shorter arc indicated by dotted lines 80 b—b. By adjusting the stops with reference to the scale, the dimensions of the blank between the curve boundaries may be predetermined. The radius bar bears the scale 19, and by adjusting said bar on the swivel support 16, with relation to said scale, the dimensions of the radius can be predetermined 85 to position the work for the inner or outer cuts—i. e. the longer or shorter arcs.

A short metal clamp is fixed to the outer 90 end of the radius bar, comprising jaws 27, 28, guided by pins 29, the upper jaw 27 being hinged and passing between ears 30, projecting upwardly from the lower jaw. An eccentric or cam shaft 31, is journaled in the 95 ears 30 and operated by handle 32, to clamp the jaws upon the margin of the sheet metal to be cut. The sheet 40 is cut with two angle edges 33, (say 30° angle) and with the parallel, straight edges 34, the blank is then 100 centered and clamped on the end of the radius bar. The stops are adjusted to give the proper longitudinal dimensions, and the radius bar is adjusted to define the arcs to be cut. A spring 35 normally spreads the jaws 105 apart. With one hand the operator rotates the cutter disks and with the other he swings the radius bar on its center to carry the blank between the cutters. The rotation of the cutters is in the direction of the move- 110

ment of the radius bar, and, therefore, has a "feed" influence to draw the blank to the cutting action. The saddle is then moved to engage the other stop, and the second cut 5 is made.

The simplicity, convenience of adjustment and operation, and the accuracy of cutting are obvious.

Various changes can be made in the structure and arrangement without departing 10 from the principle of the invention.

Having described my invention, I claim:

A device for cutting sheet metal into blanks of different dimensions and of pre-
15 determined radii, comprising in combination, a marginally graduated supporting beam, a pair of cutting disks at one end thereof, stops adjustably clamping on the

beam margin, a saddle adjustable on the beam intermediate the stops, a swivel post on 20 the saddle, a graduated radius bar longitudinally adjustably clamped in the swivel post, a member on the saddle extending forwardly of the swivel post, and transversely of the beam, serving to support the intermediate portion of the radius bar in its arc 25 of movement, and a sheet metal clamp on the free end of the radius bar for holding the inner edge of the sheet to be cut.

In witness whereof, I hereunto subscribe 30 my name, as attested by the two subscribing witnesses.

CHARLES J. HOLUB.
